UNITED STATES PATENT OFFICE

ELMER J. POWELL, OF HUBBARD, OHIO, ASSIGNOR TO THE POWELL PRESSED STEEL COMPANY, OF HUBBARD, OHIO, A CORPORATION OF OHIO

TIERING LUG

Application filed January 7, 1931. Serial No. 507,219.

This invention relates to improvements in tiering lugs for tiering boxes, that is to say lugs adapted to insure proper alignment of boxes stacked one above another. The invention is intended primarily for application to sheet steel boxes employed in factories, freight terminals, and warehouses for handling and storing goods of various kinds. Often times these boxes are mounted upon elevated platforms, called lift truck platforms, for the reason that the elevator of a lift truck may be projected thereunder. The elevators of such trucks are movable to a height of from six to eight feet. The stacking or tiering of a series of box platforms, that is boxes with elevated bottoms, may be accomplished by the use of such a truck. The platform of the truck is projected beneath the bottom or platform of a box, the truck platform elevated to a sufficient height and the truck manipulated to bring the box thereon directly above a box standing upon the floor. The elevator is then caused to descend far enough to deposit its box upon the first box, when the truck platform is withdrawn by backing out the truck. Then a third box is lifted by the truck to a greater height and deposited on the second in the same manner, and so on. Boxes of this kind are tiered three to five high by the use of such a truck. The reverse operation is followed when a stack is to be taken down again. Another method is to place one box on top of another by the use of a crane, and to build up the stack in this manner. In the latter case the boxes need not have elevated platforms.

One of the objects of my invention is the provision of a tiering lug for use upon tiering boxes, which shall be economical of material, easy to construct, and capable of secure attachment to the box by welding only.

Another object of the invention is the provision of a lug of this character adapted to seat itself upon the box at two separated points, whereby strains transmitted to the lug may be very effectively absorbed by the box wall.

Other objects and features of novelty will appear as I proceed with the description of that embodiment of the invention which, for

the purposes of the present application, I have illustrated in the accompanying drawing, in which

Figure 1 is an elevational view of a platform box embodying the invention, certain of the parts being broken away and shown in section in order to more fully illustrate the construction.

Fig. 2 is a fragmental plan view of the same.

Fig. 3 is an end view of the box shown in Fig. 1, and

Fig. 4 is a fragmental vertical sectional view taken substantially on the line 4—4 of Fig. 1, showing on a larger scale the tiering lug and its attachment to the box.

In the drawing I have shown a platform consisting of a table portion 10 and side walls 11, the entire platform being supplied preferably with strengthening corrugations extending transversely and protruding downwardly and inwardly. The lower edges of the walls 11 may be bound with channel runners 12 which serve to convert the platform into a skid or sled.

The table portion 10 of the platform constitutes the bottom of the tiering box, the side walls of which may be formed from one or more pieces of sheet steel. In the box herein illustrated the complete box, aside from the bottom, is formed of a single sheet which is first corrugated and flanged at its top and bottom edges, then bent into rectangular shape, and the end edges welded together along the line 13. This joint may be reinforced if desired by the use of a flat or corrugated strip 14 extending along the seam on the inner or outer side thereof and welded at intervals to the two ends of the sheet.

The corrugations in the side walls of the box, numbered 15 in the drawing, preferably extend outwardly and are spaced apart, leaving flat wall portions 16 between the corrugations. At the bottom the wall portions are flanged inwardly as indicated at 17, affording a good surface for welding the box walls to the bottom 10. At their upper edges the wall members are provided with a ledge 18 which I prefer to form, as shown in the drawing, by flanging the metal outward horizon-

tally and then bending it under and back and downwardly against the side wall. The upper edge of the box is thus rendered quite rigid.

5. The tiering lug is indicated generally in the drawing by the reference character A. It is a heavy metal stamping which in shape resembles a chair. I prefer to employ four such stampings for every box, two on a side.

10. However a different number may obviously be used and they may be arranged differently than herein shown if desired. For some kinds of boxes it may be desirable to employ tiering lugs at the ends as well as at the sides.

Each lug has an upstanding or back portion 20, a horizontal seat portion 21 and a forward leg portion 22. The back portion is inclined outwardly more or less so as to direct 20 the superposed box into proper position when it is lowered onto the seat portion 21 of a tiering lug. The latter portion rests directly upon the ledge 18, affording means for transmitting directly downward into the 25 box wall the load of the superposed box or boxes. The leg portion 22 is of the proper length to rest upon the shelf or shoulder formed at the intersection of the uppermost corrugation 15 and the straight wall portion 16 therebeneath. The leg portion 22 is arranged at an angle to the vertical, as shown in Fig. 4, partly in order to make it engage the corrugation 15 behind the flush inner 30 surface of the wall, whereby it can transmit pressure downwardly into the wall, and partly in order to widen the seat portion 21. The attachment of the lug to the box is effected preferably by arc-welds 23 and 24 running the full width of the lug.

40. When boxes of the particular type herein illustrated are tiered with my tiering lug, the runners 12 rest upon the seat portions 21 of the lugs on the box next beneath. The contents of each box are therefore accessible, 45 provided the articles are small enough to be lifted out by a workman from one end of the box through the space beneath the platform 10 of the box next above. The invention is however applicable to boxes without platforms, in which event the bottom of each 50 box forms a lid for the box next beneath.

In the foregoing description I have necessarily gone somewhat into detail in order to explain fully the particular embodiment of 55 the invention herein illustrated, but I desire it to be understood that such detail disclosures are not to be construed as amounting to limitations, except as they may be included in the appended claims.

60. Having thus described my invention, I claim:

1. In combination with a metal tiering box having a ledge along its horizontal top surface, a tiering lug having a load receiving portion seated upon said ledge, an upstand-

ing portion at one side of said load-receiving portion, and a lower portion extending downwardly from the other side thereof, the load supporting and lower portions of said lug being attached to the box.

2. In combination with a metal tiering box, a chair-shaped tiering lug seated upon the upper edge of said box, said lug being welded to the upper edge of the box and to the side wall thereof at a point spaced from said upper edge.

3. In combination with a metal tiering box having a horizontal ledge at the top thereof, a chair-shaped tiering lug having its seat portion seated upon said ledge and welded thereto, and having a forward leg portion extending downwardly and welded at its lower edge to the wall of the box.

4. In combination with a metal tiering box, having a shoulder a short distance beneath the upper edge of the box, a chair-shaped tiering lug having its seat portion seated upon the upper edge of the box and welded thereto, and having a forward leg portion bearing upon said shoulder and welded thereto.

5. In combination with a metal tiering box having an integral ledge at the top thereof, a chair-shaped tiering lug having its seat portion seated upon said ledge and welded to one edge thereof, and having a forward leg portion extending downwardly over the opposite edge of the ledge and welded to the box wall.

6. In combination with a metal tiering box having a horizontally running corrugation near the top edge thereof providing a shelf presented toward the interior of the box, a chair-shaped tiering lug facing inwardly and having its seat portion seated upon the upper edge of the box and welded thereto, and having a forward leg portion extending downwardly to and welded upon said shelf.

In testimony whereof, I hereunto affix my signature.

ELMER J. POWELL.
